UNITED STATES PATENT OFFICE.

EUGÈNE SCHNEIDER, OF PARIS, FRANCE, ASSIGNOR TO SCHNEIDER & CIE, OF PARIS, FRANCE, A LIMITED JOINT-STOCK COMPANY OF FRANCE.

RECOIL-BRAKE FOR GUNS.

1,373,103.

Specification of Letters Patent. Patented Mar. 29, 1921.

Application filed June 16, 1919, Serial No. 304,656. Renewed February 17, 1921. Serial No. 445,852.

To all whom it may concern:

Be it known that I, EUGÈNE SCHNEIDER, a citizen of the Republic of France, residing at 42 rue d'Anjou, Paris, France, have invented a new and useful Improvement in Recoil-Brakes for Guns, which invention is fully set forth in the following specification.

The present invention relates to improvements in recoil brakes for guns such as described and claimed in my earlier application for U. S. Patent filed June 16, 1919, Serial No. 304,655, and more particularly to improvements in the constructional form of brake wherein the moderator valve is mounted on a liner and is adapted to receive a longitudinal movement from the fluid pressure.

Figures 1 and 2 of the accompanying drawings illustrate the invention in longitudinal section taken along the axis of the brake cylinder; the parts being shown in Fig. 1 in the positions they occupy at the commencement of the minimum recoil.

Fig. 2 shows the parts in the positions they occupy during the running-out movement of the gun.

Referring to the drawings, A is a brake cylinder attached to a recoiling part of the gun and carries a counter-rod B. A piston cylinder D provided with a piston head E is located within the brake cylinder and is made fast to a fixed part of the gun such as the gun cradle F. Within the piston cylinder D is a tube or liner D' the forward end of which is provided with a square tenon J' supported in a hollow axle J adapted to be rotated by means of a sector j which may be actuated by the elevating movements of the gun. The tenon and axle space are so proportioned as to permit slight longitudinal movement of the liner. One or more valve openings d' are provided in the wall of the liner adapted to communicate with piston passages e' through an opening e in the piston cylinder when brought into registry with the latter opening by rotation of the liner. D² is an extension of the liner and has a threaded engagement with the rear end of the piston cylinder D in which it is supported. H is a ring valve slideable on the extension D² and adapted to register with the piston openings e'. This valve is held under spring pressure or is loaded by means of Belleville springs h having an abutment against the flanged end of a dia-

phragm G in the rear end of the liner extension D². The counter-rod B is tapering and is adapted to throttle the brake fluid passing through the diaphragm G.

The outer end wall of the liner D' is provided with a conical surface which is adapted to seat on a correspondingly shaped surface J² formed on an enlargement of the hollow axle J. The end wall of the liner is pierced with openings g, g. Small passages j³ in the bearing enlargement communicate with groove J² and the space outside the liner D'. Passages 2 in the wall of the piston cylinder permit communication between the brake cylinder space and the piston cylinder and space in front of the counter-rod.

When the brake is set for minimum recoil as shown in Fig. 1 on recoil, the fluid pressure in the brake space a overcomes the spring pressure on valve H and fluid passes to space a' through the passages e' until the pressure on the valve H counterbalances the recoil pressure. During recoil, fluid also passes through orifice 2 into the piston space 80 around the liner D', and through passages j³, J² into the axle space where it acts on the end of the tenon J' to unseat the valved end of the liner and permits the fluid to freely enter into the liner space in front of 85 the counter-rod as the latter withdraws during the recoil.

On the gun being run-out again into firing position, the liquid forced back by the counter-rod B, will press the liner D¹ 90 against the seat J² and open passages e to the space a', while it will flow slowly from the end of the liner toward the rear chamber a' of the brake cylinder, thereby producing in the usual manner the braking of 95 the running-out movement of the gun.

What I claim is:—

In a recoil brake for guns, the combination of a brake cylinder movable with a recoiling part of the gun and provided with a counter rod, a piston cylinder therein fast to a stationary part of the gun mount and provided with a brake piston having spring pressed valve controlled passages for minimum recoil and other valve controlled passages for maximum recoil, a longitudinally movable and revoluble liner tube for receiving said counter rod and provided with orifices adapted to register with said last named piston passages, a perforated end 110

closure for said liner provided with a valve surface, a revoluble hollow bearing having a valve seat for said liner valve, a key member on said end closure received by said bearing and passages in said seat and key member communicating with the piston cylinder space and with the hollow bearing space whereby said passages in the liner are covered during running out of the gun by

fluid pressure within said liner and are un- 10 covered on recoil by fluid pressure acting on the end of said key member.

In testimony whereof I have signed this specification.

EUGÈNE SCHNEIDER.
